ROTARY ENGINE

James Jolly, Blackpool, England

Application July 31, 1945, Serial No. 607,959

1 Claim. (Cl. 123—14)

1

This invention relates to improvements in rotary internal combustion engines and rotary steam engines.

The engine according to the invention comprises a rotor rotating within a casing in which it is a gas or steam tight fit and having one, two or more chambers therein open at the peripheral surface, means for supplying the charge under pressure to the said chamber or chambers and a sliding member located close to the inlet of the charge into the chamber or chambers and in front of said inlet relative to the direction of rotation of the rotor, the said sliding member being controlled by a cam or equivalent device on or driven by the rotor shaft and timed so that it enters each chamber or pocket in a more or less radial direction immediately the front edge of each chamber or pocket has passed it and as or just before the said front edge passes the inlet of the charge and is withdrawn as the rear face of each chamber approaches it.

The front or leading face of each chamber is substantially radial and the rear thereof is arranged at such an angle that if for any reason the sliding member should fail to be withdrawn on the approach of the rear of the pocket it forms an inclined surface up which the sliding member will ride.

In the case of an internal combustion engine the charge is compressed in a cylinder the axis of which is substantially radial in relation to the rotor having a piston working therein and an inlet onto the periphery of the rotor, the piston being driven from a cam or equivalent device on or driven by the rotor shaft so that its movement is timed relative to each chamber in the rotor.

The invention is illustrated diagrammatically in and will be described with reference to the accompanying drawings in which:

Fig. 1 is a transverse vertical section through a rotary internal combustion engine the rotor of which has two chambers therein.

Fig. 2 is a side elevation thereof.

Fig. 3 is a section on line 3—3 Fig. 1.

Fig. 4 is a plan of a liner surrounding the rotor.

Fig. 5 is a transverse vertical section through a rotary steam engine, the rotor of which has three chambers therein.

Fig. 6 shows a modification of the drive for the cam operating the shutter or the piston in the cylinder.

Fig. 7 shows a gear for reversing the drive from the rotor.

In the form of the invention shown diagrammatically in Figs. 1 to 4 as applied to an internal

2

combustion engine a rotor A is carried by a shaft B mounted in bearings c in end plates C¹, C², affixed to cylindrical casing C, the ends b¹ and b² of the shaft B projecting through the bearings.

5 The rotor A is formed with two chambers A¹, open at the peripheral surface of the rotor and equally spaced around the latter. The front or leading face a of each chamber is substantially radial and the bottom a¹ thereof gradually approaches the periphery of the rotor at a much less abrupt angle for a purpose which will be hereinafter indicated.

To ensure a gas tight joint between the periphery of the rotor A and the casing C the former carries a split liner D on its periphery, the liner having apertures d therein corresponding with the open faces of the chambers A¹. The liner D is formed with radial flanges d¹ which engage annular plates c¹ on the inner faces of 10 the end plates C¹, C².

The bottom a¹ and front face a of each chamber A¹ are preferably provided with a lining a² of a suitable heat resisting metal or alloy, the lining being affixed to the rotor by the screws a³.

15 A cylinder F is formed as an extension of the casing C and a piston F¹ operates therein. The cylinder F has an inlet port f controlled by a one way valve f¹ and an outlet port f² passing through the wall of the casing C. A sparking plug f³ is arranged near the port f². The cylinder F is preferably vertical and the piston F¹ is operated by the rod f⁴, lever f⁵, connecting rod f⁶ and pivoted arm f⁷ which carries a runner f⁸ engaging in a cam groove g of a cam G affixed 20 on the end b¹ of the rotor shaft B. Since it is necessary that the piston F¹ should make as many compression strokes for each revolution of the rotor A as there are chambers A¹ therein the cam groove g must oscillate the arm f⁷ the same number of times. This may be attained in the case of the two chambered rotor shown in the drawings by rotating the cam G at the same speed as the shaft B and forming the cam groove g with two cam surfaces g¹ or by rotating the cam G at twice the speed of the rotor A and providing it with a single cam surface. In the latter case as shown in Fig. 6 the cam G is rotatably mounted on the shaft B and is driven therefrom through the gear wheel g² affixed on the shaft B, the gears wheels g³ and g⁴ affixed on the lay shaft g⁵ and the gear wheel g⁶ affixed to the cam G, the ratio of the gear being 2 to 1.

A sliding member or shutter H is arranged close to the wall of the cylinder F and in front thereof relative to the direction of rotating of the

rotor A. The member H is adapted to slide through an aperture in the casing C so that it enters each chamber A¹ in a more or less radial direction immediately the front edge a of the chamber has passed it and just before the edge passes the port f² from the cylinder to the interior of the casing C.

The sliding member H is of the same width as the width of each chamber A¹ and moves down into contact with the bottom a¹ thereof, its undersurface being shaped to conform to the contour of the bottom and its sides which contact with the sides of the chamber are preferably slightly tapered at their lower ends to ensure that it enters the chamber, the corresponding sides of which may be of corresponding taper.

The sliding member H is operated from the cam E on the end b² of the rotor shaft B through the runner e which engages in a groove in the cam, connecting rod e¹, pivoted lever e² and rod h in such a way that it receives a drive parallel to its direction of movement.

The shape of the bottom a¹ of the chamber A is such that it will gradually push the sliding member H out of the chamber should the connections from the cam E fail for any reason.

As in the case of the piston F¹ the sliding member H must make as many strokes for each revolution of the rotor A as there are chambers A¹ therein so that the camgroove must have the same number of cam surfaces or the cam H must be rotated at twice the speed of the rotor A by means similar to that described and illustrated in Fig. 6.

An exhaust port c³ is formed in the peripheral surface of the casing C at such a position that it will not be uncovered by a chamber A¹ in the rotor A until the chamber has moved away from the port f² and a second exhaust port c⁴ is formed in the peripheral surface of the casing C a short distance in front of the piston where the sliding member H passes through the casing.

In order to obtain a reverse drive from the rotor shaft B the driving shaft B¹ (see Fig. 7) instead of being integral therewith is driven therefrom through a reversing gear. The reversing gear shown in Fig. 7 comprises a clutch member K slidably mounted on the end of the shaft B but prevented from rotation in relation thereto and a second clutch member K¹ affixed on the shaft B¹. Each member carries a bevel wheel k, k¹ adapted to be engaged by a third bevel wheel k² mounted on the end of a screwed rod L carried by a frame L¹ so that by rotating the rod L by the hand wheel l the wheel k² is moved into or out of engagement with the wheels k and k¹. The sliding clutch member K is operated by a screwed rod L² through the link l¹ and pivoted lever l², the rod being rotated by the handwheel l³.

When the clutch members K and K¹ are disengaged and the wheel k² is engaged with the wheels k and k¹ i. e. the positions shown in Fig. 7 the shaft B¹ will be driven in the opposite direction, i. e. in reverse, to the shaft B. For forward drive the wheel k² is disengaged from the wheels K and K¹ and the clutch member K engaged with the clutch member K¹.

The application of the invention to a steam engine is illustrated in Fig. 5 which shows a transverse section through rotor A and casing C the rotor having three chambers A¹ equally spaced around the periphery of the rotor. In the case of a steam engine a compression cylinder is not required, the high pressure steam entering the chambers A¹ through the port f² and expanding

therein against the fixed abutment formed by the sliding member H. The member H is operated by a cam on the shaft B of the rotor A similarly to that already described and the casing C is formed with two exhaust ports c³ and c⁴. The rotor shaft B is preferably provided with a reversing gear similar to that shown in Fig. 7.

In either of the forms of the invention illustrated in the drawings an oil reservoir c⁵ may be provided in the bottom of the casing C for lubricating the liner D as it rotates in the casing.

The cycle of operations of the internal combustion engine shown in Figs. 1 to 4 is as follows:

Assuming a chamber A¹ has just passed the port f² from the cylinder F i. e. the position shown in Fig. 1 the piston F¹ commences its outward stroke, drawing a charge into the cylinder F and then compresses the charge between its face and the peripheral surface of the rotor before the next chamber A¹ approaches the port f². As the front edge a of the second chamber A approaches the port f² the sliding member H enters the chamber and forms a fixed stationary wall behind the front face a. As the port f² becomes uncovered the compressed charge in the cylinder F rushes into the increasing space between the front face a of the chamber A¹ and the stationary wall formed by the member H. The charge is fired by the sparking plug f³ as soon as the charge commences to enter the chamber A¹ and as at this period the piston F¹ is held stationary and as the rear of the chamber A¹ is formed by a sliding member H which is then fixed the whole force of the expanding gases owing to the firing of the charge is taken by the front face of the chamber or pocket and drives the rotor.

As soon as the chamber has passed the port f² the sliding member H is withdrawn and the piston F also commences its suction stroke and shortly afterwards the first exhaust port c³ is uncovered allowing the discharge of the products of combustion from the chamber A¹. The rotation of the rotor A continues until the front a of the first chamber A¹ passes the sliding member H when the same cycle of operations commences for the first chamber as has been described for the second chamber.

When the second chamber is again approaching the sliding member H the second exhaust port c⁴ is opened so that substantially all the remaining products of combustion in the chamber are swept out through the port c⁴.

The cycle of operations of a steam driven engine is similar to that described for an internal combustion engine taking into consideration that there is no compression cylinder.

In either application of the invention any convenient number of rotors may be arranged side by side and all the pistons in the compression cylinders and the sliding members may be controlled from a single pair of cams, in the case of an internal combustion engine and all the sliding members may be controlled from a single cam in the case of a steam engine.

I claim:

A rotary internal combustion engine, comprising a casing having a cylindrical chamber therein, a substantially cylindrical rotor mounted rotatably in said chamber in the casing and having a chamber in its periphery, the casing having a port for admitting an explosive medium to the chamber in the rotor, an abutment slidably mounted in the casing and movable into the chamber in the rotor, a peripherally-split cylin-

drical liner on the periphery of the rotor and having an aperture therein corresponding with the chamber in the rotor, the liner having inturned flanges at its side edges which engage the lateral peripheral edges of the rotor, and annular plates interposed between the outer sides of said flanges on the liner and the inner faces of the end walls of the casing and forming fluid tight joints between the periphery of the rotor and the casing.
